MOBILE HOME

Stanley A. Harper, Lakewood, Colo.
(8700 W. Colfax Ave., Denver, Colo. 80215)

Filed Feb. 23, 1966, Ser. No. 1,159

Term of patent 14 years

(Cl. D14—3)

FIG. 1 is a front elevation view of a mobile home embodying my new design as viewed from a standing location and would be a side elevation when traveling;

FIG. 2 is a rear elevation view of the mobile home shown in FIG. 1;

FIG. 3 is an end elevation view of the mobile home shown in FIG. 1 as viewed from a front position with respect to the direction of travel; and

FIG. 4 is an elevation view of the mobile home shown in FIGS. 1 through 3 as viewed from a rear position with respect to the direction of travel.

I claim:

The ornamental design for a mobile home, as shown.
